PIPE JAW ATTACHMENT FOR ADJUSTABLE WRENCHES

Philip C. Kine, Fort William, Ontario, Canada

Application January 9, 1953, Serial No. 330,405

1 Claim. (Cl. 81—180)

This invention relates to adjustable wrenches, and more particularly to a pipe wrench attachment which may be readily engaged on one of the jaws of a conventional adjustable wrench.

A main object of the invention is to provide a novel and improved pipe wrench attachment for an adjustable wrench of the type having a first jaw rigidly connected to the handle of the wrench and a second jaw slidably engaged with said handle through a slot therein, whereby the spacing between the jaws may be varied, the improvement being simple in construction, being easy to install on the wrench, and enabling a conventional smooth-jawed wrench to be converted into a pipe wrench when required.

A further object of the invention is to provide an improved pipe wrench attachment for use on a conventional smooth-jawed wrench to enable the wrench to be employed for gripping and rotating round objects, such as pipes or the like, the attachment being inexpensive to fabricate, being durable in construction, and being quickly installed and removable by the user.

Further objects and advantages of the invention will become apparent from the following description and claim, and from the accompanying drawings, wherein:

Figure 1 is a side elevational view of a conventional adjustable wrench provided with an improved pipe jaw attachment according to the present invention.

Figure 2 is a top view of the wrench of Figure 1.

Figure 3 is an enlarged cross sectional detail view taken on the line 3—3 of Figure 2 and showing the pipe wrench attachment installed on the stationary jaw of the wrench.

Figure 4 is an enlarged cross sectional detail view taken on the line 4—4 of Figure 1.

Referring to the drawings, 11 designates a conventional wrench having an elongated handle 12 to which is integrally connected a first jaw 13, said jaw being formed with the slot 14 which slidably receives the shank 15 of a second jaw 16, the shank 15 being provided with the rack element 17 which is engaged by the worm 18 rotatably mounted in the head of the wrench in the usual manner. As is well known, rotation of the worm 18 causes the movable jaw 16 to be adjusted toward or away from the stationary jaw 13. The jaws 13 and 16 are provided with the relatively flat gripping faces 19 and 20, whereby the wrench may be employed for gripping smooth-faced objects having flat-parallel surfaces, such as hexagonal nuts, bolt heads, and the like.

Designated at 21 is the pipe gripping attachment, said attachment comprising a block element 22 which is wedge-shaped, as shown in Figures 1 and 3, said block element being provided with the transversely serrated gripping face 23. The element 22 is adapted to engage against the gripping surface 19 of the jaw 13, as illus-

2

trated in Figures 1 and 3. At its outer end the block element 22 is formed with the upwardly projecting, rearwardly curved locking lug 24 adapted to lockingly engage with the outer corner portion of jaw 13, as shown in Figures 1 and 3. At its inner end the block element 22 is formed with the upstanding, resilient arm 25 which is engageable through the slot 14, as shown in Figures 3 and 4, the arm 25 being provided at its end with the hook element 26 which is engageable with the outer surface of the jaw 13 at the outer end of the slot 14, as shown in Figure 3.

When it is desired to employ the wrench 11 for gripping round objects such as pipes or the like, the attachment 21 is engaged thereon by first engaging the lug 24 over the outer end corner of the jaw 13 and slipping the resilient arm 25 upwardly through the slot 14, pushing upwardly on the block element 22 until the hook element 26 snaps into engagement against the outer surface of the jaw at the top end of the slot 14, as shown in Figure 3. In this position the block element 22 is held firmly against the jaw surface 19 and the attachment is securely locked to the jaw 13, whereby the wrench may be employed for gripping round objects, such as pipes, rod or the like. To remove the attachment, it is merely necessary to manually flex the arm 25 clockwise, as viewed in Figure 3, as by manually pushing the lug 26 to the right, as viewed in said figure, whereby the lug 26 may be pushed downwardly into the slot 14. With the lug 26 pushed downwardly into the slot 14, it is then merely necessary to grasp the block element 22 and to pull said block element downwardly away from the jaw 13.

While a specific embodiment of a pipe jaw attachment for a wrench has been disclosed in the foregoing description, it will be understood that various modifications within the spirit of the invention may occur to those skilled in the art. Therefore, it is intended that no limitations be placed on the invention except as defined by the scope of the appended claim.

40 What is claimed is:

A jaw attachment for an adjustable wrench of the type having a main body, a first jaw rigidly connected to said main body and formed with a slot adjacent said main body and a second jaw having a shank thereon slidably disposed in said slot, said attachment comprising a wedge-shaped block element formed with a gripping surface, said block element being shaped to fit against the surface of said first jaw, a lug at one end of the block element lockingly engageable with the end of the first jaw, a resilient arm secured to said block element in opposing relation to said lug, a hook element on the end of said arm, said arm being engageable in said slot and said hook element being engageable with the outer surface of said first jaw at the outer end of said slot to secure said block element against said first-named surface.
